UNITED STATES PATENT OFFICE

WILLIAM SCHEIBEL, OF NEW YORK, N. Y., ASSIGNOR TO BULOVA WATCH COMPANY, INC., OF NEW YORK, N. Y., A CORPORATION OF NEW YORK

DESIGN FOR A WATCHCASE

Application filed October 21, 1930. Serial No. 37,338. Term of patent 14 years.

To all whom it may concern:

Be it known that I, WILLIAM SCHEIBEL, a citizen of the United States, and a resident of the borough and county of Bronx, in the city and State of New York, have invented a new, original, and ornamental Design for a Watchcase, of which the following is a specification, reference being had to the accompanying drawing, forming part thereof.

The figure is a perspective view of a watchcase, showing my new design, the dominant features of which are shown in full lines.

I claim:

The ornamental design for a watchcase, as shown and described.

WILLIAM SCHEIBEL.
